UNITED STATES PATENT OFFICE.

JOSEPH W. FROST AND STEPHEN D. LAKE, OF ROCHESTER, NEW YORK.

AUTOMATIC ELECTRIC FIRE-ALARM SYSTEM.

SPECIFICATION forming part of Letters Patent No. 350,426, dated October 5, 1886.

Application filed December 12, 1885. Serial No. 185,474. (No model.)

To all whom it may concern:

Be it known that we, JOSEPH W. FROST and STEPHEN D. LAKE, of Rochester, in the county of Monroe and State of New York, have invented a new and useful Improvement in Automatic Electrical Fire-Alarm Systems, which improvement is fully set forth in the following specification, and shown in the accompanying drawings.

Our invention relates to automatic electric fire-alarm systems; and the object of the invention is to arrange certain improved apparatus in any given house or building in such a manner that an accidental fire or unusual heat occurring at any time in any room or apartment thereof will be quickly announced by the ringing of alarm-gongs or displaying of signals, or both, within the building, at the central office, or at other points at which such alarm apparatus may be placed for the purpose.

The object of our invention is also to arrange the wires and other devices in such manner that the particular story, flat, or section of the building at which such fire may occur will be duly announced to the observer by signals or otherwise.

The object of our invention is also to furnish a means for testing the wires, gongs, and other devices of either story or section of the building separately at any time without ringing the alarm bells at the central office, fire-department offices, or other points from the building; and the further object of the invention is to furnish means to provide against false alarms being sounded, which might otherwise be unintentionally caused by the occupants of the building, by the jarring or operation of machinery, or from other causes, the invention being fully described hereinbelow, and more particularly pointed out in the claims.

Referring to the drawings, Figure 1, Sheet 1, is a vertical section of a building, showing four stories or flats, with the apparatus of our improved automatic electrical fire-alarm system applied to each story in a simple manner, for the purpose of illustrating the application of the same; Fig. 2, Sheet 2, a front elevation 50 of an annunciator, substantially of common kind, used in connection with our fire-alarm system, the device being used, in addition to

giving an alarm, to designate the story or section of the building at which the fire may be located, the glass front of the case being 55 broken away to uncover the apparatus within; Fig. 3, a view showing the interior of the box containing the devices for testing the circuit-wires and other apparatus of each story or section of the building independently, the 60 door of said box being thrown open; Fig. 4, Sheet 3, a view of said box, seen as indicated by arrow in Fig. 3, the box being horizontally sectioned, as upon the dotted line *x* in said latter figure, one of the push-buttons or testing 65 devices being mostly broken away to uncover the wire-connection and other parts, the figure being drawn to more fully show the operation of the parts; Fig. 5, a face view of a thermostat, the same being shown and described in application for patent of date August 10, 1885, Serial No. 173,971; Fig. 6, a rear elevation, and Fig. 7, a transverse section, of the same, taken on the dotted line *y*. Fig. 8, Sheet 4, shows two simple systems of clock-work, the one at the 70 right hand being substantially that in common use in signal-boxes to strike or sound numbers upon the alarm-bell at the central office by the frequent making and breaking of the circuit, and the one at the left being a novel device 75 for regulating the giving of alarms, so that false alarms shall be avoided, parts being shown in two positions by full and dotted lines; Fig. 9, Sheet 1, an enlarged view of parts shown in Fig. 4, viewed in the same direction in which said 80 latter figure is seen, being drawn to better show the parts represented; Fig. 10, an enlarged view, it being an elevation of one of the electro-magnets and attached parts occupying the 85 annunciator-box, drawn to show the manner in which the plate or card bearing the number 90 of the story is caused to turn and face the operator, parts being shown in two positions of adjustment; Fig. 11, a view of the same, seen as indicated by arrow in Fig. 10, drawn to further show the manner in which the number is 95 exposed to view; Fig. 12, Sheet 4, a rear elevation of the annunciator, drawn to a smaller scale, showing more fully the wire-connections 100 of the separate electro-magnets within the annunciator; Fig. 13, a top view of the same, the bell-stand and other parts being omitted, drawn to further show the wire-connections; and Fig. 14, a view of a portion of the front side of the

signal-box, drawn to show the indicator or pointer which indicates the position of the alarm-regulating disk, so that its relation with the pendulum of the alarm clock-work may at 5 any time be seen.

In this fire-alarm system we arrange thermostats, preferably those shown in application serial number 173,971, in all of the rooms and apartments of the buildings or blocks supplied 10 with said system, locating said thermostats, if there be a choice, at such parts of the various rooms as there may be thought to be the most danger of fire, placing said thermostats upon the ceiling or side walls in greater or less numbers, according to the requirements of the case 15 or size of each room. These thermostats in their normal state are open and form no part of the electrical conductors. Wires from the poles of a local battery are led to pass tangentially by each thermostat, and are connected 20 with each, so that when closed by the action of heat parts of said thermostats become a portion of the conductor, short-circuiting the current and completing the connection between 25 the poles of the battery. Each story or other section of the building, as may be desired, is provided with a complete system of conductors and thermostats, with alarm-gongs, signals, and other devices, if thought necessary, each of 30 which systems forms a secondary system to that of the whole. The wires of each secondary system connect with the main wire leading from the battery, so that each of these systems will operate in giving fire-alarms, and 35 each system may be tested independently of the rest. To the primary system belongs a signal-box, from which wires lead to various alarm-bells out of the building—as, for instance, one located at the central office, which 40 may be located at a distance—one or more connected with gongs located at various fire-department buildings or other places, as the case may be. The thermostats are each joined to both of the wires leading from the respective 45 poles of the battery, so that a connection may be made between said wires through any one of said thermostats when a cause exists. The wires of each secondary system are separated and the circuits broken at the respective push- 50 buttons, and when either one of said push-buttons is pressed to close the circuit the wires and other devices forming said system are subjected to a test.

For the purpose of testing the wires, alarm-bells, &c., belonging to either of the secondary systems independently of the rest of the primary system, to see at any time if all of the apparatus thereof is in working order, we have wires leading from each secondary system 55 brought together at some convenient location, joining each to a separate circuit-closing device of some suitable kind, the same being preferably an ordinary push-button. By closing the respective circuits at these 60 points at any time a circuit will be formed, including within it the apparatus of the entire secondary system to which the push-but-

ton or circuit-closer belongs, the alarm-gongs out of the building being entirely cut out, by means hereinafter described, so that no alarm 70 will be given outside the building while making these tests. By this means a silent test (as regards the fire-department) may be had at wires, no alarms being sounded, save the striking of any time of any of the secondary systems of 75 the bells or gongs within the building belonging to the system being tested, and the annunciator is connected with each of the secondary systems, so that when a test is made of either system the number of said system 80 will be presented to view in said annunciator. If the wires of the system are not in order, the gongs forming part of the system will not sound when a test is made, and the number 85 will be displayed in the annunciator. The alarm-gongs within the building belonging to any or all of the secondary systems may be so connected as to be also thrown out of circuit when the tests are being made, should it be advisable at any time not to have them 90 sound. The push-buttons for testing are preferably arranged side by side in a closed box, the cover of which may be secured by a lock and key to prevent said buttons being tampered with, said test-box, as a matter of convenience, being placed just below or near the annunciator. To cut out the signal-box and wires leading to the alarm-bells at the central office and other points above mentioned, so that no alarm shall be given on account of the tests 100 being made, we connect branch wires to the battery-wires on either side of the signal-box, bringing the ends of said branch wires near each other within the test-box, and connect them, respectively, with other parts in the box, 105 so that they will be joined or separated by the opening and closing of the door of said test-box. By means of these devices within the test-box, operated by the opening and closing of the door of said test-box, the alarms outside 110 of the building are automatically cut out of the local circuit whenever the tests are made. On account of this arrangement of parts no 115 false alarms can, under any circumstances, be sounded from making the tests, for the push-buttons or circuit-closers cannot be operated until the door of the test-box is thrown open, which automatically closes the circuit through the branch wires above mentioned.

When this system of fire-alarms is put into 120 a building—such as, for instance, a manufacturing establishment—it might sometimes occur that by the moving or jarring of machinery, or for various unforeseen causes, an alarm might be sounded when there was no accidental 125 fire or heat to act upon the thermostats, or when no cause existed for said alarm of the nature of those guarded against; also, the operatives or other persons in and about a building supplied with this system might from accident 130 or design ring an alarm, which would lead to unnecessary loss and confusion, besides causing a lack of confidence in the system from such false alarm being given. To prevent

this we introduce into the system an alarm-regulating device which prevents the instantaneous sounding of an alarm from any cause—that is to say, on account of this regulator an alarm cannot be sounded until after the cause of such alarm has existed continuously for a period of time of certain length, previously arranged. The operation of this alarm-regulator is such that when a connection is made

10 at any point between the poles of the battery from any cause, either from accident, design, or the starting of a fire, causing a thermostat to act, an alarm will not be instantaneously sounded thereby, but instead certain machinery will be set in motion, which, after the lapse of a quarter-minute, half-minute, or other period of time, as may have been previously provided for, will cause such alarm to be sounded.

20 Referring more particularly to the parts of the invention, A, Fig. 1, are the vertical walls of a building, and B the floors thereof.

25 *a* are thermostats located anywhere thought necessary upon the walls or ceilings of the various rooms of the building, and *c* and *o*' wires of the system leading from a local battery, C.

30 D is the annunciator, preferably located in a front hall, or near a window, that it may be seen from the street by persons outside the building, should a fire occur therein in the night.

35 F is a test-box containing a number of circuit-closers, *n*, there being one for each story or section of the building supplied with an independent secondary system of alarm apparatus.

40 A' is a signal box, preferably located near the annunciator, which contains our improved alarm-regulating device, the latter being connected with and forming a part of the fire-alarm system herein described. From the signal-box two wires, *u*², run to the district office L in the usual way.

45 At H, Fig. 8, is shown the ordinary clock-work in the signal-box, having the usual break-wheel, K, and circuit-breaker *z*, for determining the strokes upon the bell at the central office, there being also attached to the clock-work the usual escapement-pendulum, N.

50 At O is shown another system of clock-work provided with a disk, S, and escapement-pendulum E, which latter clock-work forms a regulator for the operations of the clock-work shown at H.

55 T is a magnet which operates a detent, *b*', for the pendulum E.

60 The thermostat shown is composed of an annular wooden holder, *p*', holding an annular metallic frame, *k*', which latter may form at any time a part of the circuit. *i*' is a bar or spring of conducting metal secured at one end to said frame, being separated from the latter by an insulator, *m*'.

65 *l*' is a circular disk of hard rubber, being sensitive to the heat, the same being sprung into the frame *k*', taking a convexo-concave form from the strain thereon, said disk hav-

ing its concave surface turned toward said cross-bar *i*'.

n' is a screw passing through the bar or spring *i*', having its point resting against the concave surface of the disk, serving to hold the free end of said bar normally slightly away from the frame *k*' to break the circuit thereat.

70 *r*' and *s*' are two short wires connected, respectively, with the main wires *c* and *o*' of the system, which latter wires are secured to the respective posts *t*' of the thermostat, the wire *r*' being connected with the bar *i*', and the wire *s*' being connected with the frame *k*'. 80 From this it will be understood that if the disk *l*' be expanded from the action of heat it will bend farther away from the bar or spring *i*', allowing the free end of the latter to touch the metallic frame *k*' and close the circuit at 85 that point, and the signal-box, annunciator, gongs, &c., in the building belonging to the system being within the circuit will be caused to act.

85 As above stated, the secondary systems of 90 the various stories or sections of the building may at any time be tested by the devices provided for the purpose; but if when making these tests no precaution be taken to prevent, regular fire alarms will be sounded on account 95 thereof. To avoid these alarms we short-cut the circuits at the test-box F, leaving out the signal-box and all wires leading therefrom to the alarm-gongs at the central office, fire-department buildings, &c., by some means—for 100 instance, as follows:

105 *b* is a simple frame placed in any convenient place within the test-box, so as to hold a push-pin or movable part, *d*, in position to have the door G press it back when closed, as shown in Figs. 4 and 9. This push pin rests within a holder, *f*, secured rigidly within the frame *b*, around which pin and within the holder is coiled a spiral spring, *o*, pressing against a collar, *r*, of the pin, which spring tends to 110 urge the pin in a direction toward the door. The inner end of said holder is closed, save as to a central orifice in which the pin *d* rests, the latter reaching back to some distance beyond the end of the holder. To the inner end 115 of the pin a branch wire, *v*, is rigidly secured, as with solder, said wire leading from the main battery-wire at a point, *u*', on said battery-wire near the signal-box, and on the opposite side thereof from the battery, and between said signal-box and the other devices of the system on the line or battery wire, as the thermostats, gongs, &c.

120 *g* is an insulating block or stud held to the inner surface of the frame *b* by simple means, at the free end of which is secured a metallic plate, *h*, to which plate is secured another branch wire, *u*, connected with said main battery-wire at a point, *v*', between the signal-box and the battery. The signal-box being 125 between the points *v*' and *u*', (where the wires join,) when the circuit is closed in the test-box the signal-box, with the connected outlying wires, will be left out. When the door of the

test-box is opened for the purpose of making the tests above mentioned, the spring *o* will force the push-pin outward sufficiently to bring the head *s* of said pin against the wire *u* and close the circuit between the wire *u* and *v*, leaving out the signal-box *A'*, with the outlying wires. This short-circuiting of the battery-wire will continue all the while the door is open, making the test-buttons accessible, so that in no case can any of the alarm-gongs, excepting those within the building and belonging to the system, be rung from the making of the tests.

From this description of the connection of the push-buttons with the respective secondary systems and the operation of the push-pin *d* it will be understood that any of said systems may be at any time tested without other act or operation than simply opening the door and pressing the push-button of the system to be tested.

Within the annunciator-box *D*, Sheets 1 and 2, back of the glass front thereof, there are placed as many electro-magnets *B'* as there are stories or sections in the building furnished with independent secondary systems. To each magnet is added a disk or card, *x'*, upon which several cards, respectively, are written the numbers of the stories or sections supplied with the independent secondary systems. These cards or disks are each secured to a simple frame, *d'*, fitted to turn upon a vertical rigid post, *c'*, so that the number upon the card may be presented to or withdrawn from view, as the case may be. A slender spiral spring, *a'*, secured to said frame and coiled upon the post, tends to turn said frame so as to cause the card to face the observer when standing in front of the annunciator. A horizontally-projecting arm, *y'*, is made rigid with the frame *d'*, and when said frame is turned to withdraw the number from view said arm is engaged by a catch, *z'*, formed at the extremity of an armature, *b'*. When the magnet is rendered active by closing the circuit, the armature will be drawn down, releasing the arm *y'*, on account of which the spring *a'* will quickly turn the frame *d'* upon its post and cause the number on the card to be presented to view, as stated.

The wires of each secondary system are respectively connected with the different magnets of the annunciator, as shown at *e e' e'' e'''*, so that when the circuit of any system is closed, either for making a test or from the action of a thermostat, the corresponding number will be displayed, as stated, and the gong of the annunciator struck, the latter being in every circuit.

The annunciator shown, or any other of the different styles of annunciators in use with electrical systems, may be used in our automatic fire-alarm system, said annunciator here shown not being held to be new or novel, and the same forming no part of our present invention.

Referring to the clock-work *O* in Fig. 8, the disk *S* is secured rigidly to the shaft *g'*, to

which shaft also the ordinary actuating-spring for the gearing is secured, the other end of the spring being connected with the gear *R*, all in the usual manner. The gear *R* is fitted to turn freely upon the shaft *g'*, said gear being provided with the ordinary pawl, *k*, and pressure-spring *i*, while the opposing inner face of the disk *S* is provided with ratchet-teeth *l*, to act with the pawl *k*. From this it will be understood that by turning said disk, with its shaft, around in the direction indicated by the dotted arrow the spring will be wound or strained, and when left to itself will tend to turn the gear *R*, by means of the pawl and ratchet, in the usual manner. The disk *S* is circular and has one or more notches, *p*, formed in its periphery, and the gearing *O* is relatively so placed that said disk occupies the vertical plane in which the pendulum *N* swings, the axis of said disk being about on a level with the lower end of said pendulum. At its lower end, at *t*, the pendulum is turned laterally toward the disk, and the latter is so placed that said pendulum can vibrate only when a notch, *p*, is opposite the part *t* thereof. At all other times the unbroken circular periphery of the disk crowds the pendulum and prevents said vibrating of the same. Thus the disk forms a stop for the pendulum and stays the motion thereof, and the motion of the connected gearing and break-wheel *K*. The pendulum *E* is at times prevented from vibrating by means of a stop, *b'*, which latter is held to bear against said pendulum, by means of a slender spring and thread, *d'*, said thread being wound upon a pin, *f'*, in the usual manner, to regulate the tension upon the thread and spring. The electro-magnet *T* is held in position to attract the stop *b'*, like an armature, which latter, when thus drawn to the magnet, releases the pendulum and allows it to vibrate and start the clock-work, causing the disk *S* to present, after a time, a notch, *p*, to the pendulum *N*, as stated. The pendulum-weight *H* is adjustable upon the pendulum-rod, so that the disk *S* may be caused to turn more or less rapidly, as may be desired. While running, the clock-work carries the disk slowly around, so that it may be ten, twenty, or thirty seconds, or other period of time, as may be thought best, after said clock-work is started, before a notch is presented to the pendulum to allow the break-wheel of the signal-box to sound an alarm at the central office.

The operation of the parts is substantially as follows: When the circuit is closed at any one of the thermostats, or by other means, the magnet *T* becomes active and starts the clock-work shown at *O*, the movement of which in course of time allows the clock-work at *H* to move and sound an alarm at the central office, all as stated.

It will be seen that on account of the disk *S* and the action generally of the clock-work *O* the closing of the circuit, in order to sound an alarm, must be continuous during a period sufficiently long to bring the notch *p* around to

- the pendulum. A brief closing of the circuit will allow the stop S to turn but a short distance, on account of which the notch will not be presented and no alarm will be sounded.
- 5 In case the circuit is closed from the action of heat upon a thermostat, it will, of necessity, remain closed sufficiently long to bring the notch *p* to the pendulum. The clock-work at O can only move while the circuit is closed, it being 10 instantly stopped by the action of the spring *d* in drawing the detent *b* against the pendulum, when the magnet is rendered inactive from the circuit being broken. To arrest the motion of the disk or stop S at the point at 15 which the notch *p* shall stand opposite the pendulum, we secure a stop-pin, *a'*, to said disk, in position to encounter a rigid stud, *c'*, projecting from some fixed part of the device. The disk being held in this position allows the break-wheel K to turn several times 20 around, repeating the alarm at the central office as many times as may be desired. After an alarm has been sounded the attendant turns the disk S back to its normal position, in the direction indicated by the dotted arrow, to carry the notch *p* around away 25 from the pendulum and bring the unbroken portion of the periphery of the stop S against the pendulum, as stated, so that the apparatus shall be in position to give another alarm or 30 operate again. To turn the disk backward, a simple key may be placed upon the squared end *f*² of the shaft *g*' in the usual manner. When the disk S is in its normal position, the 35 notch *p* is at a distance from the pendulum N— as, for instance, it may be diametrically opposite said pendulum—so that a period of time— say twenty seconds—shall elapse before it can be brought around to the pendulum to allow 40 an alarm to be given; but if, from various causes, a number of brief closings of the circuit shall be effected, each allowing the clock-work to move a short distance, altogether carrying the notch around to a point near the 45 pendulum, another brief closing of the circuit from accident might be sufficient to carry the notch to the pendulum, and so sound an alarm when there was no fire. To guard against this we attach an indicator to the shaft carrying 50 the disk, by means of which the position of the notch with reference to the pendulum may at any time be known. The indicator *g*², Fig. 14, is placed so as to point to the notch, and turns upon the outside of the case or box inclosing 55 the clock-work. By observing the indicator the attendant is enabled to see at any time the exact position of the notch, and to bring it back to its normal position with the key, if it has been moved therefrom from any cause.
- 60 It may be desirable to cut the magnet T out of the circuit for the purpose of avoiding the resistance it offers to the current after the disk S has been brought to the position shown in Fig. 8, and the action of the clock-work and said magnet is no longer required. To allow this we make use of a spring-terminal, *h*², having one end attached to circuit-wire *e*, and
- the other end, as indicated in dotted lines, Fig. 8, in contact with loop *i*² of circuit-wire *h*². The pin *a'* may be made to open the circuit, 70 as shown, by crowding the spring *h*² away from the loop *i*² of the conducting-wire *h*², leading to the magnet. When the spring *h*² is released, on account of the disk being turned backward to its normal position, as above stated, said 75 spring, from its own elasticity, will return to the loop *i*², and again close the connection between the wires *c* and *h*².
- If a circuit be at any time closed by the action of a thermostat—as, for instance, the one at F', Fig. 1—the current will flow as follows: from battery C along wire *c*, through signal-box A', wires *u*², to and from the central office through wires *c*, continued from signal-box to thermostat F', thence back along wire *o'*, 80 touching the other side of said thermostat, to annunciator D, and along wire *o'*, continued to the other pole of the battery. The circuit thus closed serves to give the alarm at the central office by sounding upon the bell 85 thereat the number of the building at which the danger exists, and to display at the annunciator within the building the numeral or figure indicating the particular section or part of the building in which the thermostat has 90 closed the circuit, besides striking the bell I at the annunciator and giving such other signals addressed to the ear or eye as may have been previously made part of the system of 95 the section, or connected therewith.
- If it be wished to at any time test any of the secondary systems—as, for instance, the one occupying section No. 3—the circuit including 100 said system will be closed at push-button No. 3, when the flow will be as follows: from battery along branch wire *u*, through test-box F, along branch *v* to main wire *c*, along the latter to the farthest thermostat F' of the section 3, thence along the wire *c*, continued to the said testing push-button, thence back along the 105 parallel wire *o'* to the thermostat F', continuing along said wire *o'* to the annunciator D, and to the other pole of the battery along the wire *o'* continued thereto. All the other 110 circuits may be similarly traced.
- 115 What we claim as our invention is—
1. In an electric alarm system, the combination of the circuit-wires *u* *v*, the plate *h*, attached to one of said wires, the insulated block *g*, to which said plate is secured, the frame *b*, which supports said block, the push-pin *d*, which makes electrical connection between the other wire and said plate, the spring *o*, which moves said push-pin to effect such connection, and the inclosure F, having a cover, G, the opening of which leaves said spring free to act as stated.
  2. In an electric alarm system, an inclosure, F, containing wires *u* *v*, respectively connected with a battery-wire, *c*, at points on opposite sides of the signal-box of said system, test-buttons *n*, connected, respectively, with different sections or parts of said system by current-conductors, and a push-pin or movable holder,

d, for the wire *v*, and a cover for said inclosure, in combination with a holder for said wire *u* and generating-battery, said wires *u v* being connected or disconnected by the holder 5 *d*, substantially as and for the purpose set forth.

3. In combination with the battery and current wires of an automatic electric alarm system, a signal-sending device having a system of clock-work, *H*, provided with a break-wheel, 10 *K*, and co-operating circuit-breaker *z*, and a second system of clock-work, *O*, provided with a moving part, *S*, constituting a detent for the escapement *N* of said clock-work *H*, a detent for the escapement of said clock-work *O*, and 15 magnet to move said last-named detent, substantially as described and shown.

4. In combination with the battery and current wires of an automatic electric alarm system, a signal-sending device having a system 20 of clock-work, *H*, provided with a break-wheel, *K*, and co-operating circuit-breaker *z*, and a second system of clock-work, *O*, provided with a turning disk, *S*, constituting a detent for the escapement of said clock-work 25 *H*, said disk having a peripheral notch, *p*, serving to release said escapement as the disk moves around, substantially as shown and described.

5. In combination with the battery and current wires of an automatic electric alarm system, a signal-sending device having a system 30 of clock-work, *H*, and a second system of clock-work, *O*, provided with a turning disk, *S*, constituting a detent for the escapement of said clock-work *H*, said disk having a projecting pin, *a'*, magnet *T*, and wires *h'* and *c*, the latter being formed with a spring-terminal, *h'*, arranged to be struck by said pin *a'*, and moved for opening the circuit which includes magnet *T*, substantially as and for the 35 purpose set forth.

6. In combination with the battery and circuit wires of an electric alarm system, a de-

vice for sending signals having a system of clock-work, *H*, provided with break-wheel 45 and co-operating circuit-breaker, and a second system of clock-work, *O*, provided with a disk, *S*, constituting a detent for the escapement of said clock-work *H*, said disk having a peripheral notch, *p*, serving to release said escapement as the said disk moves around, and a stop, *c'*, for the disk, serving to hold said notch *p* opposite said escapement, substantially as and for the purpose specified.

7. In combination with the battery and circuit wires of an electric alarm system, a device for sending signals having a system of clock-work, *H*, provided with break-wheel and co-operating circuit-breaker, and a second system of clock-work, *O*, provided with a disk, 50 *S*, constituting a detent for the escapement of said clock-work *H*, said disk having a peripheral notch, *p*, serving to release said escapement as the disk moves around, and an indicator, *g'*, for the disk, substantially as and for 55 the purpose set forth.

8. In combination with the battery and current wires of an electric alarm system, an inclosure, *F*, containing wires *u v*, connected with one of the main battery-wires at different points thereon, test-buttons *n*, connected, respectively, with different sections of said system, a push-pin, *d*, holding the wire *v*, a holder for the wire *u*, a cover for said inclosure serving by its movements to operate said push-pin to connect or disconnect said wires *u v*, and line-wires *u'*, connected with said battery-wire between the points at which said wires *u v* join said battery-wire, substantially as described and shown.
